UNITED STATES PATENT OFFICE.

LEWIS M. HAUPT, OF PHILADELPHIA, PENNSYLVANIA.

JETTY OR BREAKWATER.

SPECIFICATION forming part of Letters Patent No. 687,307, dated November 26, 1901.

Application filed April 6, 1901. Serial No. 54,625. (No model.)

To all whom it may concern:

Be it known that I, LEWIS M. HAUPT, a resident of Philadelphia, Pennsylvania, have invented a new and useful Improvement in Jetties or Breakwaters, which invention is fully set forth in the following specification.

This invention is an improvement upon that secured to me in Letters Patent of the United States bearing date April 3, 1888, and numbered 380,569, for a dike or breakwater, and combines the general laws and principles stated therein, with the additional factors evolved from further research into and experience with the actual movements of currents in the open sea, as well as under the restraining influences of curved directrices, augmented by the force of gravity, operating on a descending instead of an ascending gradient, also by reversing the usual order of constructing said directrices by beginning to create the reaction and performing the work first on the outer or downstream face of a bar instead of the inner or land slope. The extensive works which have been constructed in this department of applied science during the past score of years have served to demonstrate the great expense and impracticability of securing self-maintaining channels by the use of parallel or convergent jetties in pairs, whether straight or curved, whatever may be their height, and it has been found necessary to have recourse to dredging to create and maintain channels of sufficient dimensions to meet the present demands of commerce. These dredges are in themselves expensive to build and maintain, and the channels created by them on straight lines being artificial are constantly tending to shift to the natural curves demanded by the local conditions of the site. Thus increasingly larger sums are required annually for the creation and maintenance of channels by mechanical devices in consequence of the demands due to the greater draft of vessels, while the same or even more capacious natural channels might be secured by the application of the combined static and dynamic forces of gravity, momentum, impact, reaction, and other hydromechanical agencies inherent to flowing water.

Before describing the improvement in detail it is important to note that the alluvial

bars obstructing ocean commerce are of two classes—viz., one known as the “drift and wave” bar, caused by the deposit in front of the entrance of beach sand or “littoral drift” carried by waves, tides, and currents along-shore, the other known as “delta-bars,” formed from the sediment brought down by the land-drainage and deposited in front of the mouth of silt-bearing streams. The first class is dependent for its depth over the bar upon tidal movements and is therefore found at tidal estuaries or inlets. The second depends upon the fluvial waters and is located at the mouth of rivers. The source of the material forming the bars in these cases being different the treatment must vary accordingly.

The devices embraced in my former patent were chiefly applicable to tidal inlets and were especially designed to arrest and control the littoral drift, to utilize the tidal energy by opposing as little resistance as practicable to the free ingress of the tides to the interior bays, that the volume of the movement at ebb might not be impaired; also, that the proposed channel might be defended from the encroachment of the sand drifting along the coast and that the ebb discharge might be confined to a limited sector of the bar, and thus its effective work (as compared with that of the flood) be made the greater, or, in other words, the conditions of equilibrium of the flood and ebb should be changed in favor of the ebb forces.

In this improvement the purpose is more particularly to apply the energy of the fluvial waters, charged with their own sediment, in such manner as to create erosion, produced by the concentration and reaction of a permanent opposing medium placed in or near their path and resulting in the deposition of sediment upon the opposite flank of the channel from that upon which the artificial structure is erected. There is therefore a radical distinction in the devices applicable to these two classes of maritime works and in the method of applying these jetties or tools, as well as in their form and location. In the first case (see Patent No. 380,569) the structure is detached from the shore-line and is composed of intersecting curves, forming cusps and having rectilinear flanks. In the

second it is attached to the proper bank of the river (whichever that may be) of which it forms an extension and is composed of a series of continuous curves connected tangentially to secure an accumulation of energy and a continuous reaction along or parallel to the axis of the proposed channel. The curvature may be increased toward the outer end of the work to compensate for the loss due to impact and friction. These objects will be more clearly set forth by the following enunciation of the laws and principles which it is intended to utilize in this invention for securing new, useful, and economic results.

First. Depth in bends.—The well-known fact that the greatest depth of water in a stream is as a rule located on the concave bank of a bend, while in the straight reaches the channel has less depth and is of uncertain position.

Second. Depth a function of radius.—That the depth in the bends for a given stage is a function of the radius of curvature and varies inversely as said radius, other things being equal. It is further observed that as the curves of the bed are stronger the more remarkable is the depth produced by a great pressure of water caused by a convergence of the water-threads toward the concave bank.

Third. Head due to centrifugal force.—That this depth is not due primarily to the surface slope of a stream which in a bend is longer on the concave bank, but to the head of water created by the centrifugal motion of the fluid, causing downward, as well as longitudinal, movements, thus producing a helicoidal resultant or boring action on the bottom. Observation on currents show that deepening increases not with the velocity of the current, but rather with the head of water working on the deepening, and especially at an increased depth.

Fourth. Work due to impact.—The rate of erosion of alluvial banks or beds is also largely due to the differences of the velocity of the filaments of an impinging stream before and after impact, and this difference is a function of the radius of the curve. Hence the sharper the curve the greater its erosive effects and the deeper the channel. In the expression $\frac{M}{2g} (V^2 - V_1^2)$ the greatest amount of work will

result from the greatest difference of velocities between V and V_1 before and after impact. If they are equal, the work will be nil. If V_1 is zero, the maximum result will be secured; but it may be excessive, injurious, or discontinuous. Hence the necessity for a careful adjustment to local requirements by the selection of curves of suitable radii. The kinetic energy will also vary with the mass M , and hence in great floods the amount of erosion in bends is proportionately increased, even to the extent of removing heavy revetments.

Fifth. Overcontraction or overexpansion.—In sedimentary rivers the banks at the outlet are natural levees constructed by the action of the stream, and any artificial aids in the shape of two jetties or levees projected seaward which are either too close together or too far apart become injurious in restricting the discharge and in creating bars in the channels above the mouth of the stream.

Sixth. Concentration.—Every silt-bearing river is merely a hydraulic conveyer, having the inherent energy to build bars or carve out channels, and a careful study of the natural agencies and conditions at work will suffice in many instances to ameliorate the crossing-bars and convert them into navigable channels. Mere narrowing is not sufficient. The threads must be made to take a convergent direction, thus increasing M and V and diminishing V_1 . This may be best secured by a single concave structure, located to produce concentration and reaction simultaneously.

Seventh. Lateral transportation.—The mouths of such rivers are obstructed by their own sediment, which is deposited by the inertia of the body of water into which they debouch. The source of the material forming these delta-bars being coincident with the stream itself, the interposition of a barrier simply to arrest this drift cannot be applied without damming up the channel. The action of the currents must be changed by a properly-located artificial curved jetty, so as to cause reaction on the bed, accompanied by a lateral transposition and deposit of the silt in quiet waters and out of the path of commerce. Thus there will be constructed automatically and without extra cost a natural bank, which must of necessity adjust itself to the regimen of the stream, since it is built by it, and which will meet its requirements far better than can be done by any auxiliary work of man.

Gravity.—It is also observed that the erosive action of a current passing over a bar is more effective on its downstream slope, where it is aided by the force of gravity, than on the flatter upstream face, where the material must be carried out over it on an ascending grade and is continually accumulating to obstruct its own path. Hence the true order of procedure in works of amelioration should be so to construct them as to begin the application of the energy of the currents by their concentration and reaction on the outer or downward face of the obstructing shoal and to increase their intensities by the landward (as distinguished from the usual seaward) extension of the works as the erosion proceeds.

Applications.—By applying these means and order of procedure the outer contours are caused to recede instead of to advance. The material is rolled downhill instead of up and is not obstructed by a constantly-augmenting deposit, which is ordinarily piled and pushed outward as the work advances.

The method of building out from the shore has invariably had the effect of pushing the crest of the bar rapidly to sea without materially increasing its depth by natural scour. In some places this advance during construction has amounted to more than half a mile a year and has aggregated three miles in the process of the work, thus adding over six miles to the length of the twin jetties in deep water and involving the useless expenditure of many millions of dollars. It is one of the objects of this improvement to avoid this difficulty.

The reversal of the usual method of procedure by starting work from a floating plant on the outer or sea slope instead of from a scaffolding or tramway built out from the shore will therefore result in far greater economies and expedition in the formation of the channel and will also avoid to a great extent the erosion from cross-currents at the head of every protruded jetty, which increases the cost, as well as the accumulation of energy, which renders the construction more difficult and dangerous. Under the present system of straight or parallel twin jetties the river sediment must traverse the entire length of the work before it can escape into deep water. As this length increases with that of the jetty the water-slope is reduced, and consequently its carrying capacity is diminished, while there is no room for deposit until the deep water is reached in front of the works. The result has been either to congest the outflow by overcontraction between jetties too close together, thus damming up the river above and causing a rapid silting-up of its bed, as at the South Pass of the Mississippi, or the carrying of the sediment to sea and depositing it in front of the entrance, where a new bar is soon formed.

I am aware that single jetties have been built at the mouths of silt-bearing rivers; but they have been projected from the shore seaward in every instance, so far as records are available, or they have been curved away from the channel, thus presenting a convex instead of a concave front, or they are built submerged or else only to low water or mid-tide, and thus have failed to utilize the full tidal volume, as well as the flood-discharges, of the land-drainage, and for these and other reasons have failed to combine and utilize all the available forces of nature to produce the most economical and greatest results as to depth, capacity, and self-maintainance of channels.

In view of the variable physical conditions existing at every site each case becomes a special problem of itself, so that no one specific form can be generally applied. Hence I do not wish to be limited in the use of my invention to any particular degrees of curvature nor order of their arrangement, but desire to apply the general principles and forces already enumerated to the order of construction above specified (building from bar in-

ward) in such manner as to produce continuity of reaction across the bar, recession of outer contours, prevention of bar advance, avoidance of deep pockets at ends of work, economy in construction, and enlarged channel dimensions consequent upon this method of applying the available forces.

It is designed to make the jetty the tool through which the potential energy of the natural forces is applied to secure and maintain commercial channels, and the results are inseparably connected not only with the form of the tool, but with the manner of its application. Under these circumstances a drawing would seem to be unnecessary; but to aid in the interpretation of my invention a diagram is submitted based upon the physical conditions existing at the Southwest Pass of the Mississippi River, taken as a type. A study of the regimen of the pass itself, made from the thorough survey and report known as "Document No. 142, House of Representatives, Fifty-fifth Congress, third session," shows the relation of alinement of depths and that a mass (M) of water with a mean discharge of about two hundred thousand cubic feet per second and a mean velocity (V) of about 2.8 feet maintains a depth by impact of from seventy to one hundred feet between banks which are a quarter of a mile apart and where the radius of the bend is three miles, while a radius of 4.43 miles with the same mass maintains a mean depth of channel of sixty-six feet, having a mean width between the thirty-five-foot contours of over one thousand feet. On the crest of the bar four miles from land, the current being unsupported, the depths are reduced, however, by inertia of the Gulf waters to from ten to twelve feet for a distance of one mile.

In the accompanying drawings, which form part of this specification, I have for the purposes of illustration represented one application of my invention.

Figure 1 is a plan view; Fig. 2, a cross-section on line H L, and Fig. 3 a longitudinal section on the axis of the channel.

The application of the laws of hydro-mechanics to this special case would be best fulfilled by a single curved jetty A B C D, Fig. 1, starting from the outer slope of the bar at A and having in this case radii varying from three to five miles, curving toward the land's end known as "East Point" on the left or eastern bank of the pass for a distance of about two miles, and thence by a curve of an infinite radius reaching the fast land and closing the jetty completely at D. The form of jetty adapted to this location is shown in Fig. 1, where the topography is represented in five-foot contours. The proposed jetty extends from the sea-slope at A to the shore on the left or east bank at D. The channel is represented approximately in its natural condition. It is defended from the waves of the trade-winds by the projecting jetty, acting also as a breakwater and an aid to navigation,

The flexure to the westward serves to maintain an open entrance by facilitating the passage of the littoral current and the removal by it of any sediment that may reach the outer end of the jetty in course of time. The crest of the bar is ovoidal, as shown by the curve, Fig. 1. There is a littoral current moving westwardly; but the main source of the detritus is the river, which, it is estimated, carries one hundred and two million cubic yards of sediment to the Gulf annually and causes the bar to advance at the rate of one mile in twenty years. By this form of single jetty this rate will be considerably reduced and the material be diverted to the extensive mud-flats to the west of the channel, as indicated. The centers of the various arcs are indicated at E, F, and G, while their radii vary from infinity to a minimum limit to be determined by the volume and velocity of the stream.

The dotted arrows *s s s* indicate the general dispersion of the currents in a state of nature. Those which would pass to the eastward are intercepted by the jetty and confined to the channel, thus increasing the volume passing over this more-limited section of the bar. As the levee to the west becomes built up by natural deposits the scour between it and the artificial jetty or bank becomes still more effective and the channel deepens. The figures 20, 25, 30, &c., indicate the depth of water at various points. These results are indicated in Fig. 2, which is a cross-section on the line H L of Fig. 1, which shows the original bottom before improvement and the deepening from the action of the currents as controlled and regulated by the curved jetty. To expedite the formation of this channel, it may be desirable to dredge the material out, in which case it should be impounded behind the jetty and out of reach of the currents, as indicated in the dump P.

Fig. 3 is a section of the bar to illustrate the difference in the degrees of the inner and outer slopes and to show the utility of commencing the work on the outer face of the bar and working with instead of against the force of gravity. A jetty begun at A A' would have no resistance in front of it and would scour downhill, while if commenced at D D' it would be necessary to roll or carry the detached silt up and over the crest of the bar, which would form a lee to prevent further transportation and invite deposit, thus advancing the bar seaward as the work pro-

gresses. By this single curved jetty, thus located and constructed, I combine simultaneously the available natural forces of the stream to produce more rapid erosion of the channel and also one that is more readily maintained at less cost than by any known means.

Having thus described and stated the general principles upon which my invention is based, as well as their application to a special case, to which, however, I do not limit myself, I therefore proceed to set forth the claims which I desire to secure by Letters Patent, as follows:

1. A single jetty or breakwater rising to or above the high-water or flood level, composed of a combination of non-intersecting curves of variable radii; the concave side of one or more of the curves facing the current, substantially as and for the purpose set forth. 70

2. A single jetty or breakwater composed of variable radii; the length of said radii depending on and being adjusted to the volume and velocity of the currents; said jetty being built on the "windward side" of the channel 80 (as determined by the direction of the resultant, littoral forces) and having the concave side of one or more of its curves toward the current substantially as and for the purpose set forth. 85

3. The method of constructing a single jetty or breakwater by beginning the construction on the outer or down-grade slope of the bar and developing it on curved lines toward the land; the curves, or at least one of them, having its concave side toward the currents, substantially as and for the purpose set forth. 90

4. A single jetty or breakwater composed of a combination of non-intersecting curves connected tangentially and having their concave faces toward the current and their convex faces toward the resultant littoral drift to create and maintain a continuous reaction across the bar in combination with the action of gravity secured by the method of construction from the outer slope landward substantially as and for the purpose set forth. 95 100

In testimony whereof I have signed this specification in the presence of two subscribing witnesses.
